UNITED STATES PATENT OFFICE

164,623

HANDBAG

Margaret S. Chandlee, Sacramento, Calif.

Application October 18, 1950, Serial No. 12,610

Term of patent 7 years

(Cl. D87—3)

To all whom it may concern:

Be it known that I, Margaret S. Chandlee, a citizen of the United States of America, residing at Sacramento, in the county of Sacramento and State of California, have invented a new, original, and ornamental Design for a Handbag, of which the following is a specification, reference being had to the accompanying drawing, forming part thereof.

The figure is a perspective view of a handbag embodying my design.

I claim:

The ornamental design for a handbag, as shown.

MARGARET S. CHANDLEE.
